ELECTRON-TUBE RELAY

Application filed August 7, 1929, Serial No. 384,165, and in Sweden October 1, 1928.

The present invention relates to electron tube relays in which the grids belonging to two mutually parallel-connected anodes are subjected to alternating potentials having equal amplitudes but opposite phases. In this known arrangements the static characteristic of the combined relay may be represented by a diagram which is nearly parabolic and symmetrical in relation to one of the coordinate axes. On the other hand, the dynamic characteristic indicating the operation of the relays will in the known arrangement deviate from the static one, on account of the reaction exerted upon the resulting control voltage in the tubes and caused by the drop of voltage in the outer impedance of the anode circuit. The invention has for its object to establish a relation between the anode current and the grid voltage which relation is as simple as possible and is furthering the modulation or the demodulation respectively. According to the invention a compensating voltage is back-coupled from the anode circuit common to the anodes, to the two grids with the same phase and amplitude and in such a manner that the reaction of the anode load upon the control voltages is substantially compensated. Also for the dynamic characteristic one may then obtain a parabola practically completely conforming with the static characteristic which curve represents the ideal shape of a characteristic in a modulator or demodulator. This results in the disappearance of most of the higher harmonics otherwise occurring in the anode current on account of said reaction. Furthermore the advantage is gained that the relay device may be subjected to an easy and exact pre-calculation in contradistinction to the conditions in hitherto known electron tube relays used for the same purpose.

The invention will be more closely described with reference to the accompanying drawing in which Figures 1 and 2 show two known arrangements in electron tube relays of the present kind in order to render clear the operation of the invention. Figure 3 shows an embodiment of a relay according

to the invention in which the reaction of the anode load is compensated whereas Figure 4 shows a diagram of a characteristic.

In all the shown circuit arrangements the relay is composed of two ordinary three-electrode tubes 1, 1', the anodes 2, 2' of which are connected in parallel in relation to each other and also connected to the one terminal of a coil 3 the other terminal of which is connected to the positive pole of the anode battery 4. The coil 3 is inductively coupled to a secondary coil 5 from which the modulated or de-modulated oscillations may be tapped off.

In the circuit arrangement according to Figure 1 the grids 6, 6' of the two tubes are connected each to one end of the secondary coil 7 of a transformer the primary terminals 8 of which constitute the input terminals of the relay. The secondary winding 7 is provided with an intermediate tapping 9 to which a grid biasing battery 10 may be connected.

The circuit arrangement according to Figure 2 differs from the preceding one only therein that the grids 6, 6' are directly connected each to one of the input terminals 8 between which an impedance 11 provided with a middle point tapping 12 is interconnected. To said point the biasing battery 10 may be connected.

As the alternating potentials of the grids 6, 6' have mutually exactly opposite phases the static characteristic of the two tubes may in the diagram in Figure 4 be represented by two curves extending symmetrically in relation to one of the coordinate axes. In the diagram V_r represents the amplitude of the control alternating voltages according to the formula

$$V_r = V_g + \frac{V_a}{\mu} \dots \text{ and } \dots V_r' = -V_g + \frac{V_a}{\mu} \quad 1$$

relating to the two tubes, 1, 1'. The relations between the anode currents of the tubes represented by i_a , i_a' , and the control alternating voltage V_r and V_r' respectively may be analytically expressed through the formulas;

$$\left. \begin{array}{l} i_a = C_o + C_1 V_r + C_2 V_r^2 + C_3 V_r^3 + \dots \\ i_a' = C_o' + C_1' V_r + C_2' V_r^2 + C_3' V_r^3 + \dots \end{array} \right\} 2$$

If the tubes are exactly equal the corresponding constants are alike.

If it is assumed that the primary circuit of the input transformer includes a high frequency generator of the frequency ω_1 and a modulating current source of the frequency ω_2 , by way of example, falling within the range of voice frequent oscillations, we have

$$V_g = A_1 \sin \omega_1 t + A_2 \sin \omega_2 t$$

According to Formula 1

$$\left. \begin{array}{l} V_r = A_1 \sin \omega_1 t + A_2 \sin \omega_2 t + \frac{V_a}{\mu} + \int V_a, \\ V_r' = -A_1 \sin \omega_1 t - A_2 \sin \omega_2 t + \frac{V_a}{\mu} + \int V_a \end{array} \right\} 3$$

in which formulas the last terms correspond to the compensating voltage transferred back to the grid circuit from the anode circuit. According to the present invention said voltage is so adjusted that

$$\int V_a = -\frac{V_a}{\mu}$$

The resulting control voltages are then

$$V_r = A_1 \sin \omega_1 t + -A_2 \sin \omega_2 t$$

and

$$V_r' = -A_1 \sin \omega_1 t - A_2 \sin \omega_2 t = -V_r.$$

The resulting anode current I_a in the coil 3 is then obtained by insertion into the Equation 2, thus

$$I_a = i_a + i_a' = 2C_o + 2C_2 V_r^2 + 2C_4 V_r^4 + \dots 4$$

Said resulting anode current is in the diagram in Fig. 4 represented by the parabolic curve drawn in full lines. In most cases it is possible in the last equation to neglect terms of higher powers than the second for which reason the curve I_a may be considered as practically an exact parabola.

The term essential to the modulation in the expression for I_a is then according to Formula 4

$$4C_2 A_1 A_2 \sin \omega_1 t \sin \omega_2 t = 2C_2 [A_1 A_2 \cos \omega_1 - \omega_2 (t - \cos \omega_1 + \omega_2 / t)]$$

As according to Formula 4 in the expression for I_a no linear terms with respect to V_r occur no currents of the frequencies ω_1 or ω_2 will be included in the anode current. In the present case the carrier wave is thus completely suppressed.

A further condition not mentioned hitherto for entirely suppressing the carrier wave is, however, that the point of operation is displaced along the characteristic curve of the electron tube relay which condition may be fulfilled by a suitable selection of the grid direct current biasing voltage according to

Figure 4 so as to obtain said point at the vertex of the parabola, (A in Figure 4), or in other words in such a way that the resulting control direct current voltage

$$V_{R\bullet} = 0, \text{ i. e. } V_{go} = -\frac{V_{ao}}{\mu}. \quad 70$$

The suppression of the carrier wave brings certain advantages in case the modulating oscillations, according to the invention, are transferred from a modulator to a power amplifier before they are supplied to an antenna or the like. By the suppression of the carrier wave the power amplifier is, namely, unloaded therefrom and operates thus more economically.

In case the reaction of the anode load upon the control alternating voltages V_r and V_r' had not been eliminated by rendering

$$\int V_a = -\frac{V_a}{\mu},$$

the control alternating voltages would have been functions of the anode current as $V_a = Z_a I_a$ in which expression Z_a designates the outer anode impedance. When adding the Equation 2 the result would thus be an implicit expression with respect to the anode current. The pre-calculation of the apparatus is thus rendered difficult and the explicit solution with respect to I_a will contain also terms which are not negligible. By compensating the reaction of the outer anode impedance in above described manner according to the present invention said inconvenience may, however, be eliminated and a dynamic characteristic coinciding with the static characteristic of the desired pure parabola shape is obtained. To bring about said compensation one may according to the invention as shown in Figure 3 include a retransfer coil 13 in series with the grid biasing battery 10 which coil is inductively coupled to the primary coil 3. The degree of coupling between the coils 3 and 13 is so adjusted that the reaction of the anode load is substantially compensated which occurs if the retransferred voltage $\int V_a$ is made equal

$$-\frac{V_a}{\mu}. \quad 105$$

In this case the control voltage contains only those frequencies which are supplied to the input terminals 8, whereas the frequencies of the control voltage generated by the reaction of the anode circuit are completely eliminated. The circuit diagram according to Figure 3 is otherwise identical with that in Figure 2.

By the compensation or the compound coupling according to the invention in a relay connected as shown in Figure 1 or 2 a complete elimination of the entire spectrum of higher harmonics is obtained which otherwise would occur on account of the reaction

of the anode circuit. The arrangement may also be subjected to a completely exact pre-calculation.

In addition to the above manner of compensating the reaction of the anode circuit upon the grid circuit there are also other possibilities conceivable to obtain nearly the same result of the compensation. One may, by way of example, use so called shielding grid tubes in which, by the disposition of a fourth electrode of a constant potential in the tube, the reaction of the anode circuits upon the grid circuit to a certain degree is compensated.

In certain cases it is, however, not desirable to suppress the carrier wave. The point of operation should in such a case not fall at A but be displaced, by way of example, to the point A' in Figure 4. Also in this case, however, a modulated oscillation in the anode circuit is obtained, because the dynamic characteristic is practically an exact parabola, which oscillation is free from harmonics and is proportional to the product of the amplitudes of the modulating and the modulated grid alternating voltages. Such an absence of higher harmonics is, on the other hand, not obtained in hitherto known embodiments of electron tube relays for modulation or demodulation.

I claim:

An electron tube relay comprising two anodes connected in parallel relatively to each other and two grids which latter are subjected to voltages of the same amplitudes but of opposite phases relatively to each other characterized in that a compensating voltage from the anode circuit common to the anodes is transferred back with the same phase to the two grids in such a manner that the reaction of the anode load upon the control voltages is substantially compensated.

In testimony whereof I affix my signature.
MAURITZ VOS.
